MARINE MOTOR

Harry L. Johnson, Waukegan, Ill., assignor to
 Johnson Brothers Engineering Corporation,
 Waukegan, Ill., a corporation of Indiana

Application August 17, 1931, Serial No. 557,568

10 Claims. (Cl. 115—41)

This application is a continuation in part of my application for Marine motor, Serial 292,876 filed July 14, 1928, Patent Number 1,943,323 of January 16, 1934.

This invention relates in general to propulsion devices for water vehicles and more particularly to a submersible propeller carrying unit mounted for steering at the rear of the water vehicle, its propeller driven by the prime mover thereof, and arranged to tilt upwardly to avoid obstructions such as sand bars, logs, and the like.

A principal object of the invention is in the provision of a prime mover such as an inboard or outboard type of motor which has a propeller and a driving connection therewith, and an adjustable anti-torque plate whereby the side thrust or torque of the propeller is substantially corrected or equalized permitting the propeller carrying unit to turn as easily in one direction as the other.

Another object of the invention resides in the novel mounting of the engine or its casing directly upon the transom or hull of a boat and in securing a propeller driving unit thereto, a portion of the unit being mounted to tilt upwardly about a horizontal axis and rotatable for steering.

Other objects of the invention will appear hereinafter, the accompanying drawing illustrating a preferred embodiment of the invention.

In the drawing Fig. 1 is a side view partly in section showing the invention; and Fig. 2 is a detail of the anti-torque plate.

In operating a marine motor of this type which has a propeller carrying unit rotatable for steering, it is found that the rotation of the unit is easy in one direction and hard in the other due to the side thrust or torque of the propeller dependent upon the direction of rotation of the propeller. To counteract or equalize this unbalanced condition it is necessary to provide an unbalanced resistance, such as an obstruction on the unit, or to incline the unit, or a portion of it, or to provide an anti-torque plate as shown and described herein which may be adjusted or set at different angular positions.

Referring now more particularly to the drawing, a water vehicle 2 of any type may be provided directly at its stern or, if desired, within a recessed portion of the stern with a propulsion device comprising a gas engine having one or more cylinders 4. An engine drive shaft 6 has the usual combined flywheel and magneto 8 at one end which may also include

a rope starter plate. In addition there are the usual adjunctive devices such as the gasoline supply tank 10, a carburetor 11, and an exhaust muffler 12 which discharges through an exhaust pipe 14 extending through the rear of the boat. 60

Cooling water for the engine is drawn upwardly by means of a pump through a pipe 32 extending through the bottom of the boat and is circulated through the water jacket of the engine and thence discharged through a pipe 34 65 into the muffler 12 and with the gas discharged through the muffler pipe 14 at the back of the boat.

This propulsion device which drives the boat forwardly or rearwardly consists in general in 70 a submersible unit which has mounted therein and preferably enclosed in a water-tight casing or housing, a substantially vertically disposed driven shaft 16. This shaft and an enclosing housing 18 which surrounds it is formed 75 at its lower portion of appropriate stream line contour above and below an integral anti-cavitation plate 20 which is located at or slightly below the normal water level and includes also a lower stream line casing portion 22 and a substantially rounded stream line propeller carrying casing 24 which houses the substantially horizontal propeller shaft on which is mounted a propeller 28 at the rear thereof. The front of this housing is closed by a rounded cap 30, 85 all of the parts making a water tight casing.

The propeller shaft is geared by means of the usual bevel drive to the lower end of the vertical shaft 16 and the path of the blades of the propeller 28 is directly beneath the anti-cavitation plate 20. At the rear of the plate 20 is an anti-torque plate 25 adapted to be secured in different angular positions at the under side of the plate 20 by means of a fastening bolt or screw 26 so that it may be adjusted for a propeller which turns in one direction or the other and may also be adjusted at different inclinations to equalize the side thrust or torque of the propeller, which will permit the casing 18 to turn as easily in one direction as in the other 100 for steering the boat. If properly adjusted, steering of the lower unit becomes so free that the boat will drive straight ahead without holding the steering wheel or other steering gear.

The submersible driving unit tilts upwardly 105 to avoid damage by contact with obstructions such as sand bars, rocks, floating logs and the like, and for this purpose a sturdy bracket 36 is attached at the stern of the boat which has a stationary housing part 38 extending out- 110

wardly. This housing 38 has a circular sealing groove 40 for making a rotatable connection for a complementary housing portion 42 adapted to turn about a horizontal axis transverse to the center line of the boat. Mounted in the housing portions 38 and 42 upon the turning axis of the latter is a transverse shaft 48 which carries a bevel gear 50 having double or opposite bevel teeth meshing at one side with a bevel gear 56 attached to the end of the engine shaft 56 and the teeth on the other side meshing with a bevel gear 58 on the upper end of the driven shaft 16.

The sealing groove connecting the two housing portions permits the portion 42 to swing about the shaft 48 as an axis and relatively to the stationary housing 38. During this swinging movement the bevel gears 56, 50 and 58 are continually in mesh so that the driving connection between the engine and the propeller 28 is unbroken at any time.

At the upper end of the gear casing 18 is a hollow tube 70 to which the lower casing portion is releasably attached by any fastening means such as the screws 71 and the hollow tube is rotatable in the casing portion 42 for turning the lower unit about a vertical axis for steering. In the upper end of the tube 70 is a roller bearing 66 for the upper end of the shaft 16 and the outside of this tubular casing has a shoulder 72 for limiting the insertion of the tube 70 in the casing 42. Attached to the upper end of the tube 70 within the casing 42 is a worm gear 76 held in place by a nut 78 which connects the casing tube 70 and the lower unit for turning movement in the casing portion 42. This worm gear 76 meshes with a small pinion on shaft 82 substantially at right angles thereto and terminating in a clutch socket 84 outside of the housing 42 and adjacent to the rear of the boat. This clutch socket engages a corresponding clutch member on shaft 86 which extends to the inside of the boat where it is provided with a driving sprocket 88 which may be rotated by means of a suitable flexible chain from any desired location in the boat. By turning the sprocket 88, the lower propeller carrying casing and the propeller 28 are turned angularly by the vertical drive shaft 16 for steering. The clutch socket 84 permits free connection and disconnection of this steering mechanism during the tilting movement of the submersible unit.

The upper portion of the lower tilting unit is provided with an undercut collar 90 adapted to engage a thrust plate 92 on a stationary bracket 94 mounted on the stern of the boat or formed as a part of the stationary housing 38. This construction holds the lower unit in vertical position against the thrust plate 92 during the ordinary operation of the boat, but when the steering mechanism turns the lower unit in position to reverse the direction of movement of the boat in the water, the plate 92 will engage between and under the portions of the collar 90 and will prevent outward tilting movement of the submersible unit.

To mount this marine motor in a boat the engine casing or frame may have a flange 5 secured to the inside of the boat transom 3 by fastening devices 7, and the engine may be additionally braced or supported in the boat by a standard 13. Attached to the flange 5 from the outside of the transom by fastening means 35 is a flange of the bracket 36, so that the 75 inboard engine is rigidly attached to the transom, the propeller unit is rigidly attached to the engine, and the engine casing closes the opening in the transom so that even if the outer unit is removed the transom opening will be closed. By mounting the entire marine motor directly upon the transom its installation is much simplified requiring no stuffing box or packing, and locates the engine at the stern giving more room in the boat, and requiring no long exhaust or water connections.

By this construction the torque produced by the motor and by the rotational movement of the propeller which tends to turn the boat out of its true forward course may be effectively equalized and overcome for turning the lower driving unit as easily in one direction as in the other for steering. With a propeller turning in the left hand direction, the anti-torque plate 25 is set at an angle to the right and for a propeller turning in a right hand direction the plate is set at an angle to the left. The plate may be set at different angles for propellers of different size and for engines having different torque so that the deflecting tendency may be entirely equalized and counter-balanced without affecting the steering, tilting or reverse movement and so that the steering becomes so free that the boat tends to drive straight ahead without undue pressure on the steering mechanism in either direction.

I claim:

1. In a device of the class described, the combination of a water vehicle having a gas engine provided with a horizontally disposed shaft, a propeller carrying housing adapted to be submerged in the water beneath the lower end of said water vehicle and including a substantially vertically disposed driven shaft operatively connected with the horizontal shaft, means for turning said propeller carrying housing for steering, an unbalanced resistance on said housing for counteracting propeller torque, and means constructed and arranged to permit said propeller carrying housing to tilt upwardly about a transverse horizontal axis substantially above the level of the water vehicle, and means for disconnecting the steering mechanism during the tilting movement.

2. The combination with a boat, of an engine fixed therein having a horizontal shaft extending in a fixed location through the stern, a normally vertical propeller carrying casing and means for rotating it about a vertical axis for steering, means on said casing for counteracting propeller torque, a vertical shaft in the casing, a driving connection between the shafts, and means for mounting the casing and its normally vertical shaft to tilt upwardly with respect to the fixed horizontal shaft at the stern of the boat to avoid obstructions.

3. The combination with a boat having a transom, of a motor comprising a combustion engine secured directly to the inside of the transom, a propeller driving and steering unit secured to the engine at the outside of the transom and having a propeller driving connection with the engine through the transom.

4. The combination with a boat having a transom with an opening therethrough, of a marine motor having a propeller driving unit with part thereof rotatable for steering and a combustion engine secured together and to the transom and sealing the transom opening.

5. The combination with a boat having a transom with an opening therethrough, of a marine

- motor having a propeller driving unit with a part thereof rotatable for steering and a combustion engine secured together and to the transom and one of them sealing the opening in the 5 transom. 80
6. The combination with a boat having a transom with an opening therethrough, of a marine motor having a propeller driving unit independently rotatable for steering and a combustion 10 engine secured together and the engine having a casing secured to the inside of the transom and sealing the opening therein. 85
7. The combination of an engine adapted to be fixed to a boat, of a driving unit dirigibly 15 turnable for steering independently of the engine, a propeller and propeller shaft, means including gearing in said driving unit for connecting said engine and propeller shaft, a tiller for controlling said lower unit for steering, and 20 a deflector plate in the propeller slip stream set at an angle to the direction of travel and arranged to assist the tiller in overcoming torque developed in said gearing. 90
8. In a device of the class described, the combination of a water vehicle having a gas engine 25 provided with a horizontally disposed shaft, a propeller carrying housing adapted to be submerged in the water beneath the lower end of 10C
- said water vehicle and including a substantially vertically disposed driven shaft operatively connected with the horizontal shaft, means for turning said propeller carrying housing for steering, and an unbalanced resistance on said housing for counteracting propeller torque. 95
9. The combination with a boat, of an engine fixed therein having a horizontal shaft extending in a fixed location through the stern, a normally vertical propeller carrying casing and means for rotating it about a vertical axis for steering, means on said casing for counteracting propeller torque, a vertical shaft in the casing, and a driving connection between the shafts. 100
10. The combination with a water vehicle having an engine therein provided with a horizontally disposed shaft, a propeller carrying housing adapted to be submerged in the water beneath the lower end of said water vehicle and including a substantially vertically disposed driven shaft operatively connected with the horizontal shaft, means for turning said propeller carrying housing for steering, and an unbalanced resistance on said housing for counteracting propeller torque, and means for fixedly adjusting the resistance with respect to the housing for correspondingly varying the resistance thereof. 105
